UNITED STATES PATENT OFFICE

ROBERT D. W. VROOM, OF WALLINGFORD, CONNECTICUT, ASSIGNOR TO H. L. JUDD CO., INC., OF NEW YORK, N. Y., A CORPORATION OF DELAWARE

DESIGN FOR A SUSPENSION BRACKET

Application filed November 5, 1929. Serial No. 33,337. Term of patent 7 years.

To all whom it may concern:

Be it known that I, ROBERT D. W. VROOM, a citizen of the United States, and a resident of Wallingford, in the county of New Haven and State of Connecticut, have invented a new, original, and ornamental Design for a Suspension Bracket, of which the following is a specification.

Reference is had to the accompanying drawing, forming part thereof, wherein

I claim:

The ornamental design for a suspension bracket, substantially as shown.

ROBERT D. W. VROOM.
